(57) **CLAIM**

The ornamental design for an autonomous vehicle, as shown and described.

DESCRIPTION

FIG. 1 is a left front perspective view of an autonomous vehicle, showing the new design.

FIG. 2 is a left side view of the autonomous vehicle design of FIG. 1, and,

FIG. 3 is a rear view of the autonomous vehicle design of FIG. 1 with the hood raised to illustrate the top of the vehicle.

Applicant disclaims: the color shown in the attached drawings; the leaping Deere logos; the “John Deere” logo and stripe on the side; the shape of the side vent immediately below the “John Deere” logo on the side; the shape of the wheels and tires; the fuel fill spout on the top left side; the tubular side bumpers; and the vent openings on the top.
